G. C. ADAMS.
CREMATION FURNACE.
APPLICATION FILED APR. 17, 1916.

Patented Jan. 16, 1917.

FIG. 2

FIG. 3

INVENTOR
GEORGE S. ADAMS

PER Mr. Wright.

אַתְּ־י

UNITED STATES PATENT OFFICE.

GEORGE C. ADAMS, OF SAN FRANCISCO, CALIFORNIA.

CREMATION-FURNACE.

1,212,307.

Specification of Letters Patent. Patented Jan. 16, 1917.

Application filed April 17, 1916. Serial No. 91,763.

To all whom it may concern:

Be it known that I, GEORGE C. ADAMS, a citizen of the United States, residing at San Francisco, in the county of San Francisco 5 and State of California, have invented new and useful Improvements in Cremation-Furnaces, of which the following is a specification.

The present invention relates to improvements in cremation furnaces.

One of the objects of the invention is to provide a furnace so constructed that fluid fuels can be burned therein without noise and vibration.

15 A further object is to effect perfect combustion of the material in the furnace and to prevent unconsumed material escaping therefrom in the form of smoke.

A further object is to provide means 20 whereby the gaseous products of combustion of the furnace can safely, and without objectionable result, be discharged into the sewer.

A further object is to provide means for 25 easily removing the ashes from the furnace.

A further object is to conserve the heat generated by the combustion of the fluid fuel.

A further object is to prevent the fire box 30 or furnace pit from becoming overheated.

In the accompanying drawing, Figure 1 is a vertical transverse section of my improved cremation furnace; Fig. 2 is a horizontal section on the line 2—2 of Fig. 1; 35 Fig. 3 is a broken side view thereof; Fig. 4 is a vertical section of a door.

Referring to the drawing, 1, 2 indicate the side walls and 3, 4 the end walls of a furnace. Said side walls are connected at the 40 top by an arch 5 and are strengthened by means of stay plates 6 held together by bolts 7. The end wall 3 has an opening therethrough which is closed by a removable door 8.

45 9 indicates a fire box or furnace pit between the thickened lower portions of the side walls, the sides of which pit have upward extensions 10, of about six inches in height, into the casket chamber 11 between the narrow upper portions of the side walls, so that the casket can rest upon a number 50 of transverse bars 12 resting upon the tops of said extensions. The provision of bars at the top of a deep pit is of importance. 55 By this construction the casket can fall to

the bottom of the deep pit at a comparatively early stage in the cremation. When it has so fallen the combustion is confined to the pit, and the upper parts of the furnace are not excessively heated. This not only 60 effects a saving in heat, but also permits of a fresh casket being placed in position more quickly, because the upper part of the furnace is not so hot as it would otherwise have been. Another important result of supporting the casket upon the bars at the top of the pit is that the casket is thereby raised above the sides of the pit about an inch, and the effect is to spread the flames to the 65 sides of the casket, so that the flames entirely envelop the casket, and the casket is quickly consumed and falls to the bottom of the pit. Said extensions are thus extended longitudinally past the ends of the fire box or furnace pit 9, as shown at 13. 70 Extending through the lower portion of the side wall 1 is a horizontal hole 14 through which extends a burner 15 for burning fluid fuel, said burner, when in use, extending into the fire box or furnace pit 9. Said 75 burner is formed at the inner end with a downwardly directed tip so that the flames are discharged downward into said fire box or furnace pit, being deflected from its bottom and rising upward and enveloping the 80 casket, the products of combustion escaping by a flue 16 in the side 2 of the furnace opposite to said burner. By this construction the flames are first directed downward and then reflected from the bottom and 85 travel upward, so that the streams of incandescent gases move in opposite directions and impinge against one another and prevent the roaring or vibrating effect which would otherwise be produced by said gases. 90 For supplying air for further combustion of the fluid fuel I provide long and narrow air conduits 17 at the sides, controlled by doors 18 and leading to the bottom of the fire box. I also provide long and narrow 95 air flues 20 at the terminal portions of the sides which lead upwardly and discharge into the casket chamber near the ends of the extensions 13. I also provide long, narrow flues 19, 21, controlled by suitable doors and 100 leading to opposite sides of the furnace pit, and discharging into the casket chamber 11 on the outer sides of the extensions 10 and 13. These auxiliary air conduits supply air 105 for perfect combustion of the smoke or un- 110

consumed material in the casket chamber, so that the gases which escape by the flue 16 contain no unconsumed material.

Making the air conduits or flues 17, 20, 19, 21 long and narrow has the effect of distributing the air where required, and also of heating it very thoroughly, since the whole of it is in close proximity with the brick work. The air supply, being admitted below the casket, is preheated before being used for combustion and flows in the opposite direction to the flame proceeding from the burner, so that a thorough mixture of the flame and air, and a thorough combustion of the oil in the flame are insured. Heretofore the air and flames have flowed in the same direction and have not been so thoroughly mixed.

The provision of the flue 21 discharging on one side of the top of the pit and the flue 19 discharging into the outlet flue on the other side of the pit prevents any smoke escaping therefrom. Moreover the air inlet openings extending vertically and longitudinally in the brick work separate the outer parts of the brick work from the inner, and permit the brick work to expand by heat.

Said flue 16 is formed in the side wall 20 with ends which converge to each other, and the outer end of the flue connects with a conduit 22 which leads to a cooling chamber 23 in which are baffle plates 24 extending alternately from opposite vertical sides of the box, leaving openings between the ends of said baffle plates and the opposite walls of the box, there being provided above said openings and also over the outlet 26 of the box, sprayers 27 for discharging water spray downward into the box, so that the products of combustion are compelled to pass two or more times through said water sprays, becoming thereby cool. The products of combustion are drawn from the box and from the furnace into the box by means of a suction fan, not shown, and discharge into a sewer. The suction fan, being placed on the outer side of the cooling box, receives the gases only after they have been cooled, and is therefore not injured by the heat.

In order to readily recover the residual ashes, and also the metal parts used in the casket, the bottom 28 of the furnace pit slopes downward from each side of the furnace pit 55 to the center, and also from the middle of the furnace to the ends, and at the ends there are provided recesses 29 in which are placed metallic receptacles 31 so arranged that molten solder or other metal runs down the bottom 60 of the furnace pit into said boxes. The boxes when cooled can readily be removed through doors 32 at the ends of the furnace.

It is of advantage to have the furnace pit bottom slope downwardly from the center to the ends, as it causes the flames to spread 65 more evenly along the bottom. If the bottom were level, the tendency would be to concentrate the heat at a particular point of the bottom.

By reason of the flames from the burner 70 surrounding the casket on all sides, the casket and its contents are quickly and thoroughly destroyed by the fire.

I claim:

1. A cremation furnace having a casket 75 chamber and supports for a casket therein, a furnace pit below said supports, and a fluid fuel burner directed downwardly into said furnace pit.

2. A cremation furnace having a furnace 80 pit and a casket chamber above said pit, the sides of the pit having upward extensions into the casket chamber, bars for supporting a casket, supported by said extensions, the sides of the pit being otherwise disconnected with each other.

3. A cremation furnace having a casket chamber and supports for a casket therein, a furnace pit below said supports, a fluid fuel burner directed downwardly into said 90 furnace pit, and a long, narrow air conduit leading into said furnace pit below said burner.

4. A cremation furnace having a casket chamber and supports for a casket therein, 95 a furnace pit below said supports, a fuel burner directed downwardly into said furnace pit, a long, narrow air conduit leading to the bottom of said furnace pit and a long, narrow air conduit leading through the wall 100 of said furnace pit and discharging immediately beneath a casket supported upon said supports.

5. A cremation furnace having a casket chamber and supports for a casket therein, 105 a furnace pit below said supports, a fuel burner directed downwardly into said furnace pit, a long, narrow air conduit leading to the bottom of said furnace pit, an escape flue from one side of the casket chamber, 110 and a long, narrow air conduit leading through the wall of said furnace pit and discharging immediately beneath a casket supported upon said supports on the side of the casket chamber remote from said escape 115 flue.

In testimony whereof I have hereunto set my hand in the presence of two subscribing witnesses.

GEORGE C. ADAMS.
